UNITED STATES PATENT OFFICE.

DAVID WILLIAM HUDSON, OF GREEN BAY, WISCONSIN.

REEL.

1,088,282.

Specification of Letters Patent.

Patented Feb. 24, 1914.

Application filed May 5, 1913. Serial No. 765,533.

To all whom it may concern:

Be it known that I, DAVID WILLIAM HUDSON, a citizen of the United States, residing at Green Bay, in the county of Brown and 5 State of Wisconsin, have invented certain new and useful Improvements in Reels; and I do declare the following to be a full, clear, and exact description of the invention, such as will enable others skilled in 10 the art to which it appertains to make and use the same.

This invention relates to winding and reeling, and more especially to reels which are capable of contraction; and the object 15 of the same is to produce improved mechanism for contracting the circumference of a paper-winding reel at each revolution thereof, whereby the diameter of the roll of paper upon the reel will remain the same 20 regardless of the number of folds or thicknesses of paper which it contains. This object is carried out by constructing the device in the manner hereinafter more fully described and claimed, and as shown in the 25 drawings wherein—

Figure 1 is a side elevation of this machine complete, and Fig. 2 an end view thereof. Fig. 3 is a cross section on the line 3—3 of Fig. 1. Fig. 4 is an enlarged longitudinal section through the retarding and gearing mechanism hereinafter described, and Fig. 5 is a cross section on the line 30 5—5 of Fig. 1. Fig. 6 is a perspective detail of the parts shown in Fig. 5 slightly 35 separated from each other.

Mounted in bearings 1 in a framework is a shaft driven by suitable means as at 11. This shaft is made up of sections 2 of tubes connected at their meeting ends by couplings 3, the couplings on contiguous sections being bolted together as at 4. Through 40 its endmost face each coupling has a plurality of grooves 5 in which move rack bars 6, and the outer ends of the latter are connected to castings 7 which in turn are connected in pairs by plates 8 curved in cross section and coacting with each other to make up the periphery of the reel or drum proper which of course may be as long and as 45 large or small as desired. Throughout the tubular shaft extends a solid shaft 12, and at proper points in its length this solid shaft is provided with teeth 10 adapted to mesh with the teeth of the rack bars or spokes 6, 50 for which purpose the spokes in any group are disposed tangential to the solid shaft. When now the solid shaft is rotated with respect to the tubular shaft, it will be obvious that the spokes will be projected or retracted radially of the reel and the size of the latter will be increased or diminished as will be clear. When this device is used for the reception of paper rolls which are to be wound thereon in strip form, it becomes desirable that the circumference of the reel 55 shall be reduced at each revolution thereof in a manner at first above suggested, and the mechanism for automatically reducing the size of the same by drawing the spokes inward, forms the subject of the present 60 invention.

Keyed to the outer shaft 2 is a collar 13, and loose on said shaft is a gear 14 having a hub 15 which projects toward and into contact with the collar 13. Surrounding 65 said hub is a brake band 16, preferably having a lining 17, the band being in the form of a split ring with ears 18 at its extremities which are drawn together by a hand screw 19. Alongside the brake band and 70 between it and the gear 14 a disk 20 is mounted loosely around the hub 15, and pins 21 pass through the collar, the brake band, and this disk so as to cause all three parts to rotate simultaneously, while it will be clear that when the hand screw 19 is set 75 up to tighten the brake band around the hub 15, the rotation of said three parts will be communicated also to the gear 14. The periphery of the last-named gear may have 80 ratchet teeth or ordinary teeth, but in any event they are adapted to be engaged by a 85 spring-actuated pawl 22 carried by the frame as seen in Fig. 2, the disposition of this pawl being such that it checks the rotation of the gear 14, whereas the power imparted at 11 to the shaft 2 causes the rotation of the other elements above mentioned and they must therefore slip where the lining 17 embraces the hub 15. The periphery 90 of the disk is cut away as shown at 23, but otherwise it is of a circumference slightly greater than that of the outer end of the teeth of the gear, and the width of the pawl 22 is such that ordinarily its tip lies on the 95 circumference of the disk and does not engage these gear teeth. Alongside the disk is secured a sector 24 having a rounded front end or nose 25, and by preference its body is provided with a slot 26 through which 100 passes a screw 27 by means of which this sector is adjustably mounted against the 105

110

side of the disk. When now the sector is adjusted forward it reduces the distance between its nose and the forward end of the cutaway portion 23 which we will indicate at the point *a*; whereas the adjustment of the sector in the other direction increases said distance, which is the space that the gear teeth are exposed, for throughout the remainder of the periphery of the gear the 10 disk or its plate projects beyond said teeth and the pawl cannot engage them. At the outer side of said gear is formed a second toothed hub 30, or this element may be an independent gear fastened to the larger gear. 15 Meshing with it is a gear 31 which is fast on one end of a counter shaft 32 that is journaled in a plate 33, the latter being fast on the shaft 2 as shown. The other or outer end of the counter shaft 32 carries a 20 smaller gear 34 meshing with a larger gear 35 fast on the solid shaft 12. Finally, the extremity of this shaft is squared as shown at 37 for a purpose to appear.

With this construction of parts, the operation of the machine, is as follows: Power applied at 11 rotates the main shaft 2 and the parts that are fast thereon, and by means of the set screw 27 the sector 24 can be set on the disk 20 to vary the distance between 25 its nose 25 and the point *a*. The rotation of the gear 14 in the direction of the arrow, which occurs by reason of the band brake 16 frictionally engaging its hub 15, finally brings the point *a* under the tip of the pawl 32 which engages the first exposed tooth and checks the rotation of this gear. Thereafter the disk and the parts attached thereto rotate past the gear with the result that the sector 24 moves toward and finally reaches 35 the point *a* and its nose 25 lifts the pawl 22 out of engagement with the gear so that the latter resumes rotation with the other parts; and this rotation will continue until the point *a* again comes under the pawl, when 40 the operation just described will be repeated. While said gear 14 rotates with the hollow shaft, there is no effect upon the solid shaft, but when its movement is interrupted as just described, the result is as follows: The 45 plate 33 rotates constantly with the shaft, and this plate carries the counter shaft 32 and the gears 31 and 34 with it. As the gear 31 is in mesh with the hub 30 of the main gear 14, while said hub rotates with the 50 shaft there is no effect on the gear 31, but when the hub temporarily ceases to rotate and the gear 31 continues to move, the result will be that this gear will turn backward for a few teeth, and the rotation is 55 communicated through the gear 34 to the gear 35 on the solid shaft 12. The latter through the teeth 10 thereon causes the retraction of the various spokes 6 so that the size of the reel is reduced a trifle. Adjustment of the sector 24 so as to regulate the

distance between its nose 25 and point *a* will of course regulate the extent to which said spokes will be drawn inward, whereas the hand screw 19 need be adjusted but rarely as it is necessary that the leather 17 within the band brake 16 shall make only a slight but reliable frictional contact with the hub 15 of the main gear 14. On the other hand, after the reel has performed its work and has been reduced in circumference, 70 it may be desirable to apply a wrench or other square instrument to the end 37 of the inner shaft 12, and rotate the same rapidly in a reverse direction so as to distend the spokes 6 and enlarge the reel for renewed use; and during this action it may be wise to loosen the hand screw 19, although the same is not absolutely necessary. The parts are of the desired materials, and it will not be necessary for the purposes of this specification to amplify the uses of such a reel. 80 85

What is claimed as new is:

1. In a reel of the class described, the combination with a tubular power shaft carrying radial guides, rack bars mounted in the latter and carrying plates at their outer ends, and a solid shaft mounted through the tubular shaft and having teeth engaging those of said rack bars; of a ratchet gear loose on the tubular shaft, connections between it and the solid shaft, friction clutch devices connecting said gear with the tubular shaft, a pawl adapted to engage the teeth of said gear, and means for disengaging it intermittently and automatically. 95

2. In a reel of the class described, the combination with a tubular power shaft carrying radial guides, rack bars mounted in the latter and carrying plates at their outer ends, and a solid shaft mounted through the tubular shaft and having teeth engaging those of said rack bars; of a ratchet gear loose on the tubular shaft, connections between it and the solid shaft, friction clutch devices connecting said gear with the tubular shaft, a disk carried by said clutch devices and whose periphery projects beyond the teeth of the gear except at one point where it is cut away, a sector adjustably mounted on said disk for regulating the size of said cut-away portion, and a pawl whose tip rides on the edge of said disk and is adapted to be raised by the front end of said sector. 100 110 115

3. In a reel of the class described, the combination with a tubular power shaft carrying radial guides, rack bars mounted in the latter and carrying plates at their outer ends, and a solid shaft mounted through the tubular shaft and having teeth 125 engaging those of said rack bars; of a ratchet gear loose on the tubular shaft, connections between it and the solid shaft, friction clutch devices connecting said gear with the tubular shaft, a disk carried by said

clutch devices and whose periphery is larger than said gear but is cut away through an arc at one side, a sector having a beveled nose at its front end and a slot through its body, a setscrew through said slot and into the disk whereby the distance of the nose from the front end of said cutaway portion may be adjusted, and a pawl whose tip rides on the edge of said disk and is adapted to 10 be raised by the nose of said sector.

4. In a reel of the class described, the combination with a tubular power shaft carrying radial guides, rack bars mounted in the latter and carrying plates at their 15 outer ends, and a solid shaft mounted through the tubular shaft and having teeth engaging those of said rack bars; of a ratchet gear loose on the tubular shaft and having an extended hub, connections between this gear and the solid shaft, a collar 20 fast on the tubular shaft, a band brake carried by said collar and surrounding said hub, means for adjusting the tension of said brake, a disk carried by the brake and surrounding the hub of the gear and cut away through an arc in its periphery and a pawl 25 riding on the edge of the disk and adapted to engage the teeth of said gear.

5. In a reel of the class described, the combination with a tubular power shaft carrying radial guides, rack bars mounted in the latter and carrying plates at their outer ends, and a solid shaft mounted through the tubular shaft and having teeth 30 engaging those of said rack bars; of a ratchet gear loose on the tubular shaft and having an extended hub, connections between this gear and the solid shaft, a collar 35 fast on the tubular shaft, a band brake carried by said collar and surrounding said

hub, means for adjusting the tension of said brake, a disk carried by the brake and surrounding the hub of the gear and cut away through an arc in its periphery, a sector 45 adjustably mounted on one side of the disk and having a beveled nose at its front end, and a spring-actuated pawl adapted to engage the teeth of the gear when it comes opposite the cut-away portion in the disk and be raised out of such engagement by the 50 nose of said sector.

6. In a reel of the class described, the combination with a rotary tubular shaft having radial guides, drum-sections whose spokes are mounted in said guides, and a 55 solid shaft passing through the tubular shaft and connected with said spokes for drawing them inward; of a ratchet gear loose on the tubular shaft, friction clutch mechanism between this shaft and the gear 60 for rotating the latter with the former, means for checking this rotation intermittently, a small gear carried by the hub of said ratchet gear, a gear fast on the solid shaft, a plate fast on the tubular shaft between said gears, a counter-shaft journaled through said plate, a gear on one end of said shaft meshing with the gear which is driven by the ratchet gear, and a gear on the other end of the shaft meshing with the gear 65 which is on the solid shaft, for the purpose set forth.

In testimony whereof I have hereunto set my hand in presence of two subscribing witnesses.
